CLAIM

The ornamental design for a light set, as shown and described.

DESCRIPTION

FIG. 1 is a perspective view of a light set showing my claimed design;

FIG. 2 is another perspective view thereof;

FIG. 3 is a front elevational view thereof;

FIG. 4 is a rear elevational view thereof;

FIG. 5 is a left side view thereof;

FIG. 6 is a right side view thereof;

FIG. 7 is a top plan view thereof;

FIG. 8 is a bottom plan view thereof; and,

FIG. 9 is a local enlarged view of FIG. 2 thereof.

The broken lines depict portions of the light set that form no part of the claimed design.

1 Claim, 9 Drawing Sheets
